SASH FASTENER

John M. Kuebler, Wausau, Wis.

Application January 19, 1935, Serial No. 2,469

1 Claim. (Cl. 292—238)

The invention relates to sash fasteners.

The object of the invention is to provide a sash of the uncounterweighted type which has good weather sealing properties and at the same time may be held in different open positions. While pawl and ratchet sash-fasteners are not broadly new, most of these are not suitable for use in private homes because of unsightly exposed parts. According to the present invention 10 the sash-fastener elements are concealed in the window sash and one of these elements forms a part of the weather seal.

The invention further consists in the several features hereinafter set forth and more particularly defined by the claim at the conclusion hereof.

In the drawing,

Fig. 1 is an elevation view of a sash structure embodying the invention, parts being broken 20 away and parts being shown in section;

Fig. 2 is an enlarged detail view similar to Fig. 1 with parts shown in section as indicated along the line 2—2 of Fig. 3;

Fig. 3 is a detail transverse sectional view 25 taken on the line 3—3 of Fig. 2;

Fig. 4 is a detail transverse sectional view showing certain modifications.

Referring to the drawing, the numeral 5 designates the fixed frame and 6 the window sashes 30 slidably mounted in said frame. The lower sash is mounted to slide between guide strips 7 and 8 at the sides of the fixed frame 5 and the upper sash is mounted to slide between the extension of the guide strip 8 and frame strip 9. The 35 features hereinafter described may be used with either the upper or lower sash, but they have been shown more in detail in connection with the lower sash.

Each sliding sash has a mortise or vertically 40 extending groove 10 at each side thereof and a member 11 is disposed therein and secured to the fixed frame 5 and cooperates with the sash to form a part of a weather seal. In Fig. 4 the member 11 has been shown as disposed in close 45 relation to the sides of the groove 10 to provide a weather seal while in Figs. 1 to 3 the member 11 has a flexible facing in the form of metal strip portions 12 which are preferably formed as a part of a U-shaped sealing member whose 50 base is engaged by the strip or member 11 and held in place by said strip which is secured to the fixed frame by screws 13. It is to be noted that strip portions 12 of the U-shaped sealing member 14 have the flat parts 15 and the parts 55 inclining from said flat parts to the base of said

member and tending to exert an outward tension on said flat parts so as to prevent air passing around the sides of the groove 10.

It has been previously noted that the invention is directed to sash of the uncounterweighted type, i. e. there are no counterbalancing weights or springs to assist in holding the sash in any position of vertical adjustment, and as a consequence a sash fastener has to be provided for holding the sash in open position. According to 10 the present invention the member 11 which is preferably of wood is formed with one or more locking notches 16 and ratchet or stop notches 17 on its inner face adjacent the inner side of the groove 10 and cooperates with a gravity ac- 15 tuated metal latch member 18 which is mounted to swing in a mortise 19 in the sash upon a metal pivot pin 20 which is disposed in a bore 21 in said sash which extends on both sides of said mortise. This latch 18 has a constant tendency 20 to swing into a locked or stop position and is adapted to be released therefrom by an actuator in the form of a pin 22 screwed into or otherwise suitably fastened to said latch at a point offset from its pivot and working in a slot 23 in 25 the sash. To hold the pin 20 against working loose and to prevent wear of the pin 22 at the ends of the slot 23, a plate 24 is secured to the sash by screws 25 and projects over the exposed end of the bore 21 and has a slot 26 therein 30 alined with the slot 23 and through which the pin 22 extends.

Thus when the latch 18 is in the lower notch 16 the sash is closed and locked except against opening from the inside and the upper notch 16 35 also provides for locking it in a partially open position which opening is not large enough to permit tampering with the latch from the outside. On a release of the latch 18 from either of the notches 16 the sash may be raised and 40 held in various positions of vertical adjustment by the latch engaging in any one of the notches 17, it being noted that said latch will ratchet past these notches 17 as the sash is raised and automatically drop into a lower one of said 45 notches as the sash is lowered and that for releasing the latch 18 from either the notches 16 or 17 the operator pushes the pin 22 upwardly and thus swings the latch 18 outwardly away from the member 11 which it has been noted also 50 forms a part of the weather seal.

I desire it to be understood that this invention is not to be limited to any particular arrangement of parts except in so far as such limitations are included in the claim.

What I claim as my invention is:

In a structure of the type described having a fixed window frame provided with latch engaging portions and a sliding sash having a mortise disposed intermediate thereof and a slot extending from said mortise to one side of said sash, the combination of a gravity actuated latch cooperating with the latch engaging portions of said window frame and working in said mortise,

a pin mounted in said sash and on which said latch is pivotally mounted, an actuating member secured to said latch and projecting through said slot in said sash, and a metal plate secured to said sash and having a guide slot for said pin 5 aligned with said slot in said sash and a part projecting over said pivot pin to retain it in position.

JOHN M. KUEBLER.
